CLAIM

The ornamental design for a combined bottle and cap, as shown and described.

DESCRIPTION

FIG. 1 is a perspective view of a combined bottle and cap showing our new design;

FIG. 2 is a perspective view thereof, wherein the cap is opened;

FIG. 3 is a front view thereof;

FIG. 4 is a rear view thereof;

FIG. 5 is a right side view thereof, the left side view being a mirror image of right side view;

FIG. 6 is a top plan view thereof; and,

FIG. 7 is a bottom plan view thereof.
